UNITED STATES PATENT OFFICE.

JAMES McNAMEE, OF BALLSTON SPA, NEW YORK.

KNITTING MACHINE.

Application filed August 29, 1927. Serial No. 216,175.

This invention relates to knitting machines of the spring-needle cylinder type for producing circular knit fabrics and it relates more particularly to machines for knitting 5 porous fabrics or fabrics having relatively large openings at predetermined points. The invention is primarily an improvement upon the structures disclosed in my Patents Nos. 810,794 of January 23, 1906, and 1,050,970 of 10 January 21, 1913, and a patent issued to Bernard M. Shea on January 18, 1916, No. 1,168,- 684 and assigned to me.

One of the objects of the invention is to provide a circular knit or cylinder machine having a novel arrangement of feeds and transfers whereby a relatively large hexagonal aperture may be knit into a fabric at predetermined points without the necessity of cutting any of the threads, it being necessary to 20 utilize only a single elongated loop in the formation of each opening, said loop being carried across a plurality of courses and wales while all the remaining loops are confined to their particular courses and wales.

25 A further object is to provide a machine of this character utilizing a transfer of novel construction the working parts of which are all located inside of the cylinder, said transfer being made up of separate parts whereby 30 a single elongated loop can be placed successively in engagement with needles at opposite sides of the loop engaging needle and there held during the carrying forward of the knitting operation.

35 A further object is to provide a transfer mechanism which will operate at high speed with maximum efficiency.

With the foregoing and other objects in view which will appear as the description proceeds, the invention resides in the combination and arrangement of parts and in the details of construction hereinafter described and claimed, it being understood that changes 40 in the precise embodiment of the invention herein disclosed, may be made within the scope of what is claimed, without departing from the spirit of the invention.

In the accompanying drawings the pre-

ferred form of the invention has been shown.

In said drawings,

20 Figure 21 is a similar view showing the relative positions of the needles during the first portion of the second transfer of the long loop.

25 Figure 22 is a view similar to Figure 21 showing the relative positions of the needles upon the completion of the transfer of the long loop.

Figure 23 is a view of the needles positioned as in Figure 22 showing the long loop in engagement therewith.

30 Figure 24 is a view similar to Figure 23 showing the relative positions of the needles and the long loop after the transfer has been completed and the needles have been released.

35 Figure 25 is a view of a portion of the fabric having a course of slightly elongated loops approaching the second feed.

Figure 26 is a view showing the action of the plugged stitch wheel.

40 Figure 27 is a similar view showing the action of the cut presser wheel.

Figure 28 is a similar view showing the result produced by the action of the cast-off wheel at the end of the second feed.

45 Figure 29 is a similar view showing more or less in diagram the position of the elongated loop of the first course following the first transfer after leaving the second feed.

50 Figure 30 is a view similar to Figure 9 showing the position of the elongated loop of the first course following the second transfer.

55 Figure 31 shows the relative positions of the parts following the action of the stitch wheel of the third feed in the formation of the third course.

Figure 32 shows the relative positions of the parts following the action of the cut presser wheel of the third feed.

60 Figure 33 is a view showing the relative positions of the parts following the action of the landing wheel of the third feed.

65 Figure 34 is a view showing the relative positions of the parts at the end of the fourth feed and following the formation of the

fourth course and the completion of the hexagonal opening in the fabric.

As hereinbefore stated this invention is of the cylinder or circular spring-needle type of machine utilizing spring needles, 70 the cylinder rotating from the left to the right. Each course in the knitting operation is produced by a group of cooperating parts commonly known as a "feed". Each feed includes a push-down, a stitch wheel, a presser, a landing wheel, and a cast-off wheel. The functions of these parts are well known to those skilled in the art. In the manufacture of plain cloth on a standard circular spring needle machine one or more of 75 these feeds are used. Ordinarily three, four or five are employed, each forming a separate course of new stitches or loops. However the number of feeds employed is determined usually by the diameter of the 80 knitting cylinder. In carrying out the present invention four feeds are necessary and, for the purpose of varying the pattern, one or more additional plain feeds can be used, this number determining the amount of plain 85 cloth between the horizontal rows of openings formed by the mechanism constituting the present invention.

For the purpose of properly illustrating 90 the present invention five feeds have been disclosed, three of these feeds being of the plain or standard construction. In the drawings these feeds have been designated at A, B, C, D and E respectively. The cylinder of the machine has been indicated at 1 and 95 is provided with a circular series of spring needles indicated at 2 which, as customary, are provided with depending beards 3. Ordinarily these needles are all of the same length but in the present construction the alternate 100 needles are slightly longer than the remaining needles. In other words the second and fourth, etc., needles are slightly longer than the first and third, etc., needles. For the purposes of the present invention the needles 105 are divided into groups of four, each group including a long needle indicated at b, a short needle indicated at a, a long needle indicated at d, and a short needle indicated at c. A group of these needles has been indicated specifically in each of Figures 14 to 24 110 inclusive.

Arranged within the cylinder 1 is a supporting ring 4 to which many of the parts of the mechanism are connected. 115

First feed.

The first feed of the machine indicated at A includes the usual push-down wheel 5, located inside the circular series of needles, the 120 stitch wheel 6, the presser wheel 7, the landing wheel 8, and the cast-off wheel 9. These parts are all operated in the usual or any preferred way and produce operations well known to those skilled in the art. This feed 125

differs from that of the ordinary feed in that the stitch wheel 6 is set deeper into the series of needles than ordinarily for the purpose of supplying more than the usual quantity of yarn to the course of loops produced by the first feed. Consequently these loops will be somewhat longer than the other loops produced by the plain feeds. In this connection attention is called to Figure 25 which shows the loops X produced by this feed.

Second feed.

On passing from the first feed A the fabric comes to the feed B which not only includes 15 a push-down wheel 10 and a landing wheel 11 but also includes special constructions of stitch wheel, presser wheel and cast-off wheel. As shown in Figures 4 to 6 inclusive the stitch wheel 12 is plugged in every 20 fourth space as at 13 so that the beard of every fourth needle will be closed by the plugs and the yarn will not be carried under these closed beards. Consequently the yarn delivered to the secnd feed B is left outside 25 of the beard of every fourth needle and no stitch will be formed on these fourth needles at this point. However the stitch of the course X formed on this needle by the feed A will be retained thereon. The fourth needle herein referred to is the needle d illustrated in Figures 14 to 24 inclusive. Co-operating with the needles at the second feed, B, is a cut presser wheel 14 illustrated in Figure 9 having peripheral notches for receiving the needles a, b, and c of the groups 30 while slots 15 are provided in the periphery of this wheel for receiving the needles d. Thus, during the operation of the machine, and following the action of the stitch wheel, 35 this presser wheel will close the beards of all of the needles except the needle d which is the needle previously closed by the plugged stitch wheel. Thus the stitch of the course X formed on each needle d at feed A will 40 pass feed B without being pressed off. In other words it will be retained on the needle d. The action of the plugged stitch wheel in feed B has been illustrated in Figure 26 where the beard of the needle d is shown 45 closed and the other beards are shown open. The action of the cut presser wheel has been indicated in Figure 27 where the beard of needle d is shown open and the other beards of the group are shown closed.

50 The landing wheel 11 acts to carry the stitches from positions below the points of the beards to positions on the needles above the points of the beards. Those stitches on needles having beards which were not closed 55 by the presser wheel, will be raised inside of the beards, while the stitches on the needles having closed beards will be raised outside the beards ready to be cast off by the cast-off wheel 16.

60 Following the action of the cut presser

wheel 14 and the landing wheel 11 which leaves the yarn of the second course Y in engagement with all of the beards except the beards of the needles d the cast-off wheel 16 acts on the fabric. This cast-off wheel has only a 70 sufficient number of blades 17 to operate on the stitches carried by the needles d. These blades, which are arranged in pairs, will straddle the needles d and the stitches carried thereby, thereby producing unusually long 75 stitches at the needles d. In other particulars the feed B operates in the same manner as an ordinary or plain feed but it will be noted, by referring particularly to Figure 28, that when the course Y is completed a stitch or loop will 80 be missing from said course at each needle d and instead thereof there will be a long loop or stitch x belonging to the course X. It might be added that when these loops x are elongated during the formation of course Y 85 the remaining loops or stitches of the course X will be taken up so as to be brought to the same length as the stitches of the other courses.

Leaving the feed B the fabric now passes 90 to the transfer mechanism which is interposed between the feed B and the third feed C.

Transfer mechanism.

This transfer mechanism is made up of 95 two groups constituting respectively the first transfer F and the second transfer G. A rod 18 mounted in an integral support 19 serves to hold those portions of the transfer mechanism located outside of the circular series of needles while brackets 20 and 21 mounted on the ring 4, constitute supports for those portions of the transfer mechanism located inside of the cylinder.

Supported by the bracket 20 which, as 105 shown, straddles ring 4 and is held adjustably thereto by a set screw 22, is a vertically adjustable hanger 23 having an arm 24 adjustably mounted thereon carrying a spindle 25. On this spindle is mounted a rotatable alining 110 wheel 26 mounted for rotation by engagement with the needles 2. This wheel has peripheral teeth arranged in pairs, the teeth of each pair being indicated at 27 and 28 respectively. Each tooth 27 has one side radially disposed 115 while its other side is obliquely disposed, the two sides cooperating to produce a point. The other tooth 28 of each pair has that side nearest the tooth 27 of said pair beveled as shown particularly at 29. Thus during the 120 rotation of the wheel by the revolving series of needles 2 on the cylinder of the machine, the needles c and d of each group will enter between the teeth 27 and 28 of one pair as shown in Figure 14, needle c moving inwardly in advance of d as shown in Figure 16 while needles a and b will enter between the teeth of the spaced groups. Thus the needles will be brought ultimately to the positions shown 125 in Figure 17, the long needle d of each group 130

being disposed outside of but in contact with the adjacent needle *c* while the remainder needles *a* and *b* of the groups will lie between the teeth of adjoining pairs. The long loop α is carried by the needle *d* and by providing a small push-down wheel 30 above and in close proximity to the alining wheel 26 the fabric will be forced downwardly inside of the cylinder with the result that the long loop α will be brought down over the needle *c* as shown in Figure 18. This loop will be carried downwardly below the beards on the two needles *c* and *d* by a push-down shoe 44. Consequently as the needles are subsequently released by the further rotation of the alining wheel 26, they will spring back to normal positions, spreading the loop α so that it will be brought to one-half its maximum width. Thereafter an ordinary cast-off wheel 31 functions to elevate all of the loops so as to bring them to the tops of the needles under the beards before reaching the second transfer G. See Fig. 29.

The second transfer includes an alining wheel 32 mounted in the same way as the wheel 26 and provided with peripheral teeth arranged in pairs, one tooth of each pair being blunt as shown at 33 while the other tooth of each pair is pointed as shown at 34, the teeth of each pair being spaced from the teeth of the adjacent pair by recesses shown at 35. As the needles advance towards the second transfer the advancing needle *c* carrying the partly spread loop α will enter one of the recesses 35 while the next following needle *d* carrying the loop α will rest upon the blunt tooth 33. The next following needles *a* and *b* will assume positions at opposite sides of the tooth 34. These positions of the needles have been illustrated in Figure 21. Thereafter the long needle *d* engaging the loop α will come against a stop finger 36 and be pushed off of the blunt tooth 33 so that it will snap into the recess occupied by the short needle *a*. Thus the parts will assume the position shown in Figure 22. Thereafter the fabric will be engaged by the small push down wheel 37 which will act to turn the loop α down over the needle *a* as shown in Figure 23. Subsequently when the needles are released from the alining wheel 32, these needles will spring back to their normal positions but at this time the loop α will be in engagement not only with the needles *d* and *c* but also with the needle *a*. This will be apparent by referring to Figure 24. The loop α is of course pressed down below the beards of these three needles by a small push-down shoe 45 and then the fabric travels to the third feed C. It is to be understood of course that as the loops or stitches pass through the transfer only those loops or stitches α engaging the long needles *d* are acted on by the transfer mechanism. The other loops or stitches remain in engagement with their needles. In

Figure 29, the position of the loop α on the completion of the first transfer has been indicated while the position of the loop α on the completion of the second transfer has been indicated in Figure 30.

70

Third feed.

The third feed C is the same as a plain feed with the exception that, instead of using a plain presser wheel a cut presser wheel 38 similar to the wheel 14 is utilized. In other words this cut presser wheel has slots 39 for receiving the beards of the needles *d* so that these beards are left open while the beards of the remaining needles of each loop are closed. Consequently when the yarn of the third course C is fed to the third feed C the stitch wheel 40 will feed it to the beards of all of the needles. After leaving the stitch wheel and the push-down wheel 41 the landing wheel 42 of the feed C will lift the loops over the points of all of the closed beards so that the yarn of the third course C, following the action of the stitch wheel as shown in Figure 31 and the action of the presser wheel as shown in Figure 32, will be cast off by the wheel 43 with the loop α and one of the loops of the course C remaining in engagement with the needles *d* as shown in Figure 33.

75

80

85

90

95

Final operation.

After leaving feed C the fabric is brought to the fourth feed D where a plain knitting operation takes place, the loops of this plain course P being locked through the loops of the course C and the elongated loop α . Any desired number of these plain courses P can be employed. In the present case two such courses are provided, they being produced by the feeds D and E respectively. It will be noted that the pull exerted by the loop of course P in engagement with needle *d* will be such as to spread out the lower end of the loop α and this lower portion with the adjacent parts of the course Y and Z will produce a hexagonal opening extending through three courses and of a width substantially equal to the distance between three needles.

100

Referring to the transfer mechanism it might be stated that stationary shoes 44 and 45 constitute important parts thereof. While the push-down wheels 30 and 37 will act to bend the elongated loop α inwardly over the needles *c* and *a* respectively, the shoes act to press the loops downwardly still further to points below the beards.

105

Attention is directed to the fact that the shoes 44 and 45 and the push-down wheels 30 and 37 as well as the stop finger 36 are all carried by the rod 18 located outside of the cylinder. The alining wheels 26 and 32, however, as well as the lifting wheel 31 are all carried by the ring 4. This is likewise true of the various landing wheels and cast-off wheels. As shown for example in Figure 2

115

125

130

the landing wheel 8 is carried by an arm 46 attached to a bracket 47 adjustable on the ring 4 and held thereto by a set screw 48. This construction is similar to that illustrated 5 in Figures 11 and 12.

It is to be understood that the pattern of the cloth can be changed by changing the ratio between the number of needles in the cylinder and the number of plugs in the stitch 10 wheel, the number of cuts in the cut presser and the number of blades in the cast-off wheel, it being obvious of course that the periphery of the alining wheels will be correspondingly changed. Furthermore any desired number 15 of courses of plain stitches can be employed to vary the pattern.

Importance is attached to the fact that in the operation of the present machine at the transfer the elongated loop or stitch is first 20 carried forward to an adjacent needle and then carried backward to an adjacent needle, thereby causing the stitch to encircle three adjacent needles. The opening thus formed is further enlarged and given symmetrical 25 shape by holding this stitch down with the stitch formed in the next course, and then casting it off with the second following course.

What is claimed is:—

30 1. A knitting machine having a circular series of spring needles, alternate needles being longer than the remaining needles, means for shifting one of the needles laterally to position the long needle in lapped relation 35 with an adjacent short needle, and means for looping over the short needle the stitch carried by the long needle, said needles being adapted, when released, to spring apart to spread the engaged stitch.

40 2. A knitting machine having a circular series of spring needles mounted for rotation in one direction, alternate needles being longer than the remaining needles, means for shifting one of the long needles laterally in 45 the direction of rotation to position it in lapped relation with the next short needle in advance thereof, and means for looping over said short needle a stitch carried by the long needle, said needles being adapted, when released, to spring apart to spread the engaged 50 stitch.

55 3. A knitting machine having a circular series of spring needles mounted for rotation in one direction, alternate needles being longer than the remaining needles, means for shifting one of the long needles in the direction of rotation into lapped relation with the next adjoining short needle in advance thereof, means for looping over the short needle 60 a stitch carried by the long needle, said needles being adapted, when released, to spring apart to properly spread the engaged stitch, means for subsequently shifting the long needle laterally oppositely to the direction of 65 rotation into position in lapped relation with

the next adjoining short needle in rear thereof, means for looping over said short needle the stitch carried by said long needle and the first named short needle, all of said needles being adapted, when finally released to spring 70 apart and completely spread the engaged stitch.

75 4. A knitting machine having a circular series of spring needles, alternate needles being longer than the remaining needles, first, second and third feeds cooperating with said series of needles, each feed including a push-down, a stitch wheel, a presser wheel, a landing wheel and a cast-off wheel, the stitch wheel of the first feed being extended farther between the needles than the stitch wheel of the remaining feeds, thereby to produce longer loops than the other feed, the stitch wheel of the second feed being plugged to close the beards of selected long needles, 80 the presser wheel of the second feed being cut to release the beards of said selected needles and the cast-off wheel of the second feed being adapted to straddle said selected needles only and the stitches carried thereby, and means interposed between the second and third feeds for looping the stitches of the selected needles forwardly in the direction of rotation and backwardly in the opposite direction into engagement with the next adjoining needles. 85

90 5. A knitting machine having a circular series of spring needles mounted for rotation, first, second and third feeds cooperating with the series of needles, all of said feeds having push-down wheels, stitch wheels, pressers, landing wheels and cast-off wheels, the presser wheels of the second and third feeds being cut to hold uncompressed the beards of selected needles, the stitch wheel of the second feed being plugged to compress the beards of said selected needles and the cast-off wheel of the second feed constituting means for straddling the selected needles only and the stitches thereon, the stitch wheel of the first 100 wheel being extended farther into the spaces between the needles than the stitch wheels of the other series, thereby to produce a course of longer loops than those of the other feed 105 and to elongate selected loops by drawing yarn from the remaining long loops, and means interposed between the second and third feeds for transferring the stitches on the selected needles forwardly in the direction of rotation into engagement with the 110 next adjoining needles in advance thereof and thence in the opposite direction into engagement with the next adjoining needles in the rear thereof. 115

120 6. A knitting machine having a circular series of spring needles mounted for rotation, first, second, third and fourth feeds cooperating therewith, each of said feeds including a push-down wheel, a stitch wheel, a presser wheel, a landing wheel, and a cast-off wheel, 125 130

the stitch wheel of the first feed being extended farther between the needles than the remaining stitch wheels, thereby to produce longer loops in the fabric than the remaining feeds, the stitch wheel of the second feed being plugged to depress the beards of selected needles, the presser wheels of the second and third feeds being cut to skip the beards of the selected needles and the cast-off wheel of the second feed constituting means for straddling the selected needles only and the loops engaged thereby, and means interposed between the second and third feeds for looping the stitches on the selected needles successively forwardly in the direction of rotation to the next adjoining needles in advance thereof and thence rearwardly in the opposite direction to the next adjoining needles in rear thereof, thereby to spread the stitches of the selected needles.

7. A knitting machine including a circular series of spring needles, said series being rotatable in one direction, alternate needles being longer than the remaining needles, and means for looping a stitch from a selected long needle onto an adjoining short needle, said means including an aligning wheel inside of the cylinder provided with peripheral teeth arranged in pairs, the adjoining sides of the teeth of each pair converging toward the wheel to receive first a short needle and then the next following selected long needle and a push-down element for looping the stitch on the long needle downwardly onto the short needle lapped thereby, and means for depressing said stitch past the beards of the needles prior to the release of the needles by the aligning wheel.

8. A knitting machine having a circular series of spring needles mounted for rotation in one direction, alternate needles being longer than the remaining needles, separate feeds cooperating with the needles, and trans-

fer mechanism interposed between said feeds, said mechanism including an aligning wheel having marginal teeth engaging the needles for actuation thereby, said teeth being arranged in pairs, the advancing tooth of each pair having a blunt outer end and the other tooth of each pair being pointed, each of said blunt teeth constituting means for engaging a selected long needle while the space between the needles of the pair is adapted to receive the next following short needle, means for stripping the selected needle from the blunt tooth to position it in the recess between the teeth of each pair and in lapped relation with the next following short needle, and means for looping the stitch of the selected long needle over the lapped short needle.

9. A knitting machine including a circular series of spring needles mounted for rotation in one direction, a feed cooperating therewith for producing extra long stitches, a second feed for retaining stitches on selected needles when the other stitches are cast off at the second feed, said feed including a landing wheel for straddling selected needles and stitches, thereby to elongate the stitches of the selected needles and shorten the remaining stitches from the first feed, the yarn of the course produced at the second feed being left out of the selected needles, means for looping the stitches of the selected needles successively in the direction of rotation and oppositely to the direction of rotation to engage the next adjoining advancing and following needles, thereby to spread the stitches of the selected needles, and a third feed having means for retaining the stitches on the selected needles.

In testimony that I claim the foregoing as my own, I have hereto affixed my signature.

JAMES McNAMEE.
